WEB PASTING MECHANISM FOR PRINTING PRESSES

William A. Zalesak, Schenectady, N. Y., assignor to The Goss Printing Press Company, Chicago, Ill., a corporation of Illinois

Application March 12, 1930, Serial No. 435,122

32 Claims. (Cl. 242—58)

My invention relates to control devices, more particularly to control devices for web renewing machinery for printing presses.

One method employed for renewing the web after a roll has become exhausted is to move a fresh web roll toward the running web and paste the running web to the new fresh roll from which the web is then fed to the press. Before the 5 fresh web roll is brought into contact with the running web, it is brought up to press speed by means of friction belts or the like as is well known in the art. The running web roll from which the web is supplied to the press and the 10 fresh web roll are supported in a rotatable or pivoted support, thereby permitting movement 15 of the fresh roll toward the running web. After the paster has been made between the running web and the fresh roll, the running web is broken between the fresh roll and the exhausted 20 roll, and the web thereafter is fed from the fresh roll alone.

Various means have been developed for the purpose of performing the above operations automatically. Such devices are more or less complicated and employ cams and mechanical levers 25 and like methods. Electrical means have been employed to a more or less limited extent. The apparatus heretofore developed performs automatically one or more of the operations in making a paster but requires manual operation at 30 one or more stages during the pasting operation and the services of the attendant.

An object of my invention is to provide a novel and fully automatic web renewing mechanism for 35 making what is known in the art as a flying paster which requires only the insertion of pasted fresh rolls into the roll support of the web renewing mechanism.

Another object of my invention is to provide 40 a web renewing mechanism which is simple in structure and operation.

These and other objects will appear herein-after.

In the preferred embodiment of my invention 45 I provide a reel support provided with arms for supporting a running web roll and a fresh web roll and means electrically controlled for rotating the reel support to bring the fresh roll to pasting position and thereafter to running roll position, for bringing the fresh roll up to web speed, 50 making the paster, cutting the expiring web and applying a brake to the exhausted web roll and for thereafter controlling the speed of the web to the press. The electrical circuits to which 55 these electrical devices are connected are ener-

gized by means of a stationary contact carrying member and a member which is rigidly supported by the rotating reel and moves therewith and which carries brushes for completing the electrical circuits to the various electrical devices in the predetermined order necessary for performing the pasting operations. 5

My invention will be better understood from the following description when considered in connection with the accompanying drawings and 10 the scope will be pointed out in the appended claims.

In the accompanying drawings, Fig. 1 represents one position of the web renewing mechanism; Fig. 2 represents another position of the 15 web renewing mechanism; Fig. 3 is a detailed showing of a switch mechanism and magnetic brake; Fig. 4 is a cross sectional view of the controlling members; Fig. 5 is a front view of the brush supporting member; Fig. 6 represents the 20 electrical circuits for the control device; Fig. 7 shows a modification thereof; Fig. 8 is a showing of the contact supporting member; Fig. 9 is a detail of the web cutting mechanism. 25

Referring to Figs. 1 and 2, the stand 20 supports the reel 21 rotated by means of an electric motor (not shown) in which are mounted the running web roll 22, the fresh web roll 23, and the exhausted roll 24. These rolls are rotatably supported in the bearings 22'. The speed-up 30 mechanism 25 may be driven from the press in any suitable manner and is provided with a friction belt or belts 25' which contact with the fresh web roll for rotating the same. In my device this belt is connected to be driven from the 35 press by means of a magnetic clutch mechanism only when in contact with the fresh roll. The running web is designated by the numeral 22. A hanger frame 27 supports the pasting device 28 and the pivoted frame 26 on which is mounted the rotating belt 26' for controlling the rotation of the running web roll 22. This controlling belt or belts, a plurality may be used, is driven in any suitable manner at press speed. The electroresponsive knife means for severing 45 the web from the running web roll is also mounted on the pivoted frame 26.

In Fig. 2, the apparatus is shown in the process of making the paster. The speed-up mechanism is shown in contact with the fresh roll 23 for 50 driving the same and the pasting device is shown pressing the running web against the surface of the rotating fresh web roll for the purpose of making a paster therewith so that the new web will be furnished to the press from this fresh 55

web roll after the paster is made. The knife mechanism 29 has not yet been put into operation to sever the old web but this operation follows closely after the web is pasted to the fresh roll.

Referring to Figs. 3, 4, 5, and 6, it will be noted that the supply lines L₁ and L₂ in Fig. 6 furnish the power for energizing the various electrical devices connected thereto. The motor M rotates the reel carrying the web rolls thereon and is energized from the lines L₁ and L₂ by means of the relay 61. The purpose of introducing the relay is to prevent the contact members 51 and 52 from carrying heavy current.

The motor is energized to rotate the reel in the following manner. Referring to Fig. 3, it will be seen that a web roll is supported by means of the rotatable shaft 30 which is mounted in the bearings 22' carried by the arms of the reel.

Mounted on the top of this bearing is an automatic switch means which closes when the roll becomes exhausted.

In the preferred embodiment of my invention this switch mechanism consists of a base 31 which supports the member 32. Slidably mounted in the support 32 is the member 33 which is urged against the web roll by means of the spring 33'. Mounted in the fork portion 34 of member 33 is the rotatable member 35 which contacts with the web roll. At the other end of the slidably mounted member 33 is the portion 36 which cooperates with the slidably and pivotally mounted member 37 carrying at one end thereof a contact 39 which cooperates with the contact 40 for the purpose of energizing the motor M to rotate the reel. The member 37 carries a spring 38 which urges the member 37 in an upwardly direction against the element 33. When the web roll becomes depleted so that the member 33 may be urged to the right by spring 33', the portion 36 thereof forces the member 37 down. When the portion 36 has passed the pointed portion of the member 37 in its movement to the right, the spring 38 then causes the member 37 to pivot in a counterclockwise direction about its pivot 32' with a snap action since the spring causes the member 37 to slide quickly upward on the other side of portion 36 and thus rotate in a counterclockwise direction to close the contacts 39 and 40 with a snap action.

Referring to Fig. 6, it will be observed that when the contacts 39 and 40 are closed and the brushes 46' and 45' are in contact with the contacts 52 and 51, the action of which will be described below, a completed circuit through the relay 61 will energize the motor M to rotate the reel. The circuit controlling members which carry the contacts and the brush members which cooperate therewith will now be described by referring to Fig. 4.

The contact carrying disk 43 of insulating material is rigidly secured to the stand 20 by means of bolt 43' and carries the contact members 51, 52, 56, 57, 58, 59, 60, 53, and 55 as shown in Figs. 4, 6, and 8. This disk is mounted on the left side of the reel looking in the direction of the arrow in Fig. 2. Obviously it could be mounted on the other side. As shown in Fig. 6, these contact members are connected electrically to the various electrical parts of the web renewing mechanism. The contact members 51 and 52 are connected in the relay circuit 61 for energizing the motor M. The contact members 56 and 57 are connected to the pasting means 28. The contact members 53 and 55 are connected to the magnetic clutch

means 25 for effecting rotation of the speed-up mechanism 25 when the speed-up belts 25' are in contact with the fresh web roll. Contacts 58 and 59 are connected to the magnetically operated knife member 29 carried on the frame 26, and shown in detail in Fig. 9.

In Fig. 9, the knife 29 is pivotally supported in a mounting supported by the frame 26. The electroresponsive means 29' when energized rotates the knife mechanism 29 to sever the running web 22' between the fresh roll and the expiring web roll. The control belt for the running web roll is shown at 26'.

Contact 60 is connected to the line L₂ and with contact 59 connected to line L₁ furnishes a circuit through the brushes 49' and 48' when in contact therewith to the magnetic brake mechanism 41, and shown in detail in Fig. 3.

Referring now to Fig. 3, the rotating member 30 carries therewith the portion 42 of the magnetic brake mechanism. The portion 41 of the magnetic braking mechanism is rigidly attached to the support arms and does not rotate. Thus, when the magnetic brake is energized, the portions 41 and 42 act to brake the rotating member 30 which carries the running web roll and thus prevents further rotation of the running web roll after the paster has been made.

The member for completing the electrical circuits to the various parts of the device consists of a disk of insulating material 44 keyed to the reel shaft 21' and in which are mounted the brush members 45', 46', 47', 48' and 49', see Figs. 4, 5, and 6. These brush members are urged into contact with the contact members carried by the insulated member 43 by means of the spring 50. A cable C carries the conductors which connect with the brushes 45', 46', 48' and 49' with the knife mechanism and magnetic brake mechanism which are carried from the reel arm. This brush mechanism of course rotates with the reel. In rotating with the reel, it makes the desired connections through the contact members to produce the web pasting operation.

This brush carrying disk 44 has three sets of 45 identical brushes thereon, one set for each roll carried by the reel, it being understood that each roll is supplied with a switch and a brake. It will also be understood that the brushes make contact with the contact members for completing the electrical circuits in a predetermined order as will be described below. As has been pointed out, brush contacts 46' and 45' cooperate with the contact members 52 and 51 to complete a circuit through the relay 61 when switch 37 is 55 closed. The brush member 47' cooperates with the contacts 56 and 57 to complete a circuit through the paster mechanism 28 to energize the same. The member 48' completes a circuit through the clutch mechanism of the speed up device 25 by closing the circuit across the contact members 53 and 55. This same brush mechanism 48' at a later stage cooperates with the contacts 58 and 59 to close the circuit through the knife mechanism 29 and the contact members 59 and 60 cooperate with the brushes 49' and 48' at the same time to complete a circuit through the magnetic brake mechanism 41 which is carried on the reel shaft.

The operation of my device is as follows: When the apparatus is in the position shown in Fig. 1, the brush contacts cooperating with the running web roll 22 have the position shown in Fig. 8, in the first position as shown by the full line. It is, of course, understood that when the run- 75

ning web roll is full that the switch mechanism carried by the arm of the reel supporting this web roll is in the open position, as shown in Fig. 3. It will be observed, by reference to Fig. 6, that the circuit to the relay 61 is open and that therefore the motor M is not rotating the reel supporting the web rolls. When the running web roll 22 reaches an exhausted condition, the switch mechanism will operate to close the circuit through relay 61. It will then be seen that a circuit is completed through the switch mechanism, brush 45', contact 51 to the relay 61, through the contact member 52, the brush means 46', back to the switch. This, of course, energizes the relay to close the circuit for the motor M. The reel is then started to rotate in a clockwise direction to bring the fresh roll into contact with the running web.

As the reel rotates in a clockwise direction, the brush means 48' comes into contact with the contact members 53 and 55 as shown by the first position of dotted lines in Fig. 8. This, of course, completes the circuit through the mechanism 25 which starts the speed-up mechanism into operation by connecting to some part of the press or to a separate source for rotating the belt 25'. This takes place just about the time that the fresh web roll reaches the position of the speed-up mechanism. The fresh web roll is then started to rotate.

As the reel continues to rotate in a clockwise direction, the brush member 47' comes into contact with the members 56 and 57, as shown by the second position in dotted line in Fig. 8. This completes a circuit through the magnetically operated pasting means 28 and it operates to push the running web against the surface of the fresh web roll as shown in Fig. 2. It is understood that paste has been applied to the fresh roll on its insertion into the reel support. It will be noted that the speed-up belts are still in contact with the fresh web roll and still continue to rotate the fresh web roll.

Further rotation of the reel brings the brush member 48' out of contact with contacts 53 and 55 and into contact with the contact members 58 and 59 and the brush member 49' into contact with the contact member 60, as shown by the third position of dotted lines in Fig. 8. Thus, simultaneously, a circuit is completed through the knife mechanism 29 by means of the contact member 48' cooperating with the contact members 58 and 59 and a circuit is also completed through the magnetic brake mechanism. Thus, the web between the fresh web roll and the expiring web roll is severed, as shown in Fig. 9, and the magnetic brake is applied to prevent further rotation of the expiring web roll. The pasting means 29 is still energized for the purpose of insuring a good paste and the magnetic brake is energized a slightly longer time than the knife mechanism to insure that the roll is properly braked.

As the reel continues to rotate in a clockwise direction, the contact members 47', 48', and 49' pass out of contact with the contact members with which they cooperate, thus opening the circuit through the various devices which they control. It will be noted, however, that the contacts 46' and 45' still complete the circuit through the motor so that the motor still continues to rotate the reel in a clockwise direction and finally brings the fresh roll into running position as shown in Fig. 1, that is, the roll 23 then supplying the web to the press. When these contacts

pass out of contact with the contact members 51 and 52 and stop rotation of the reel by deenergization of the motor M, the next group of brush members for the fresh roll 23 will then be in a position shown by the first position of the brush members in Fig. 8. Of course, the switch which cooperates with the fresh web roll 23 which is now in running roll position, is open. The second set of brush members are then in a position to complete the cycle of operations just described when the fresh web roll now in running roll position becomes exhausted.

In some cases, it might be desirable to slow down the speed of the press while making the pasting. The means for accomplishing this is shown in Fig. 7 which is a modification of part of the circuit shown in Fig. 6. The press motor M₁ for driving the press has in series therewith a current limiting resistor 64 which is normally short circuited by means of the relay 63 during the operation of the press and while the paster mechanism is in normal running position. The relay 63 is in series with the electroresponsive means for energizing the clutch 25 to start the speed-up roll. Thus, as the reel rotates to bring the fresh roll against the running web, the brush member 48' completes the circuit across the contact members 53 and 55 to complete a circuit through the electroresponsive clutch mechanism and the relay 63. This, of course, energizes the speed-up belt and at the same time energizes the relay 63 to open the contacts across the resistor 64, thereby placing the resistor in series with the motor and reducing the speed of the press motor. Of course, the relay 63 is energized only so long as the speed-up belts are energized. The press could be slowed down in the same manner by placing the relay 63 in series with the pasting device 28, thus slowing down the press so long as the paster mechanism is energized.

As used in the claims, the expression "web renewing operation" includes rotating the web-roll supporting reel, rotating the fresh web roll, contacting the running web with the fresh web roll and severing the expiring web from the exhausted web roll.

The embodiment of the invention illustrated and described herein has been selected for the purpose of clearly setting forth the principles involved. It will be apparent, however, that the invention is susceptible of being modified to meet the different conditions encountered in its use and I, therefore, aim to cover by the appended claims all modifications within the true spirit and scope of my invention.

What I claim as new and desire to secure by Letters Patent of the United States, is:

1. A web renewing mechanism for a printing press having a rotatable reel supporting a running web roll in the running roll position and a fresh web roll, electroresponsive means for rotating said reel to move the fresh roll toward the running web to make the paster and thereafter to running roll position, a source of power, a circuit controlling device connected to control the supply of power to said electroresponsive means upon depletion of the running roll to rotate said reel, electrically controlled means for making the paster, a stationary contact means to which said electroresponsive means and pasting means are connected, a brush carrying member rotating with said reel, said brush carrying member cooperating with said contact means to control the supply of power to the electroresponsive means and the pasting means connected thereto.

thereto in a predetermined order for renewing the web.

2. In a web renewing mechanism for a printing press for transferring a running web from a running web roll to a fresh web roll, the combination of means for rotatably supporting a plurality of web rolls including a running web roll and a fresh web roll, electrically controlled means for moving a fresh web roll to running position, electrically controlled means for bringing the fresh web roll to running speed, electrically controlled means for pasting the running web to the fresh web roll, a circuit completing means automatically operated in response to exhaustion of the running web roll for initiating web renewing operations, a source of power, a circuit completing device, circuits connecting said electrical means and said circuit completing device, and a means in operative relation with said circuit completing means and cooperating with said circuit completing device to control energization of said electrical means in a predetermined order to transfer the running web from the running web roll to the fresh web roll.

25 3. In a web renewing mechanism for a printing press for transferring a running web from a running web roll to a fresh web roll, the combination of means for rotatably supporting a plurality of web rolls including a running web roll and a fresh web roll, electrically controlled means for moving a fresh web roll to running position, electrically controlled means for bringing the fresh web roll to running speed, electrically controlled means for pasting the running web to the fresh web roll, electrically actuated means for severing the running web from the running roll, a circuit completing means automatically operated in response to exhaustion of the running web roll for initiating web renewing operations, a circuit completing device, circuits connecting said electrical means and said circuit completing device, and a means in operative relation with said circuit completing means and cooperating with said circuit completing device to control energization of said electrical means in a predetermined order to transfer the running web from the running web roll to the fresh web roll.

4. In a web renewing mechanism for a printing press for transferring a running web from a running web roll to a fresh web roll, the combination of means for rotatably supporting a plurality of web rolls including a running web roll and a fresh web roll, electrically controlled means for moving a fresh web roll to running position, electrically controlled means for bringing the fresh web roll to running speed, electrically controlled means for pasting the running web to the fresh web roll, electrically controlled means for severing the running web from the running roll and electrically controlled brake means for the running roll, a circuit completing means automatically operated in response to exhaustion of the running web roll for initiating web renewing operations, a circuit completing device, circuits connecting said electrical means and said circuit completing device, and a device in operative relation with said circuit completing means and cooperating with said circuit completing device to control energization of said means in a predetermined order to transfer the running web from the running web roll to the fresh web roll.

5. In a control device for a web renewing mechanism employing a rotating reel, the combination of a stationary member, circuits supplied with power and terminating in said member for con-

trolling the web renewing mechanism, and a device movable with the reel for controlling energization of the circuits in a predetermined order for controlling all of the several web renewing operations.

6. In a control device for a web renewing mechanism employing a rotating reel, the combination of a stationary contact carrying member, electrical circuits supplied with power and for controlling the web renewing mechanism terminating in said contacts, and a brush member carried by the reel and movable therewith for closing said circuits in a predetermined manner to control all of the several web renewing operations.

7. In a web renewing mechanism, the combination of a rotatable support for rotatably supporting an active web roll and a reserve web roll, brake means for each roll for controlling the rotation of said rolls and means timed by the rotation of the support for applying the brake to said active roll after exhaustion.

8. In a web renewing mechanism, the combination of means for rotatably supporting an active web roll and a reserve web roll, a friction member in contact with the periphery of the reserve roll in certain positions of said reserve roll and driven by the press, a clutch controlled by the position of the reserve roll for transmitting power to rotate said reserve roll and means for engaging said clutch only when the reserve roll and friction means are in contact.

9. In a web renewing mechanism, the combination of means for rotatably supporting an active web roll and a reserve web roll, a press driven belt contacting with a web roll in reserve position, a clutch through which the belt is driven and electromagnetic means for engaging said clutch only when a roll is in reserve position.

10. In a web renewing mechanism, the combination of movable means for rotatably supporting an active web roll and a reserve web roll, brake means operating on the axial portion of the web roll and means timed by the movement of the support for applying said brake to the exhausted roll.

11. In a web renewing mechanism, the combination of means for rotatably supporting a plurality of web rolls, a device movable relatively to said web rolls and engaging the end of a web roll and a switch controlled by said device.

12. In a web renewing mechanism, the combination of rotatable supporting means for rotatably supporting a plurality of web rolls, means engaging the ends of the web rolls and individually movable axially of said rolls, means for moving said movable means and a control member operated by movement of said movable means axially of said rolls.

13. In a web renewing mechanism, the combination of means for rotatably supporting a plurality of web rolls which are successively movable into a predetermined position, a roller rolling on the end of one of the web rolls and movable axially of the roll on which the roller rolls, spring means for moving said roller and a switch controlled by bodily movement of said roller.

14. The combination with a switch adapted to control a circuit for any desired purpose, of a shoe, yielding means for holding the shoe against the end of a web roll, means connected with the shoe for controlling the switch, and means for automatically operating the switch when the web roll reaches its predetermined minimum diameter and the shoe thereby slips over the end of the roll.

15. The combination of a switch adapted to close a circuit, of a shoe held against the end of a web roll, and means whereby when the web roll reaches a diameter small enough to allow the shoe 5 to pass over its end, the switch will automatically be closed.

16. A web renewing mechanism employing a running web roll in running roll position and a fresh web roll, means for moving said fresh roll 10 toward the running web to form the paster and thereafter to running roll position, means for rotating the fresh roll to web speed before making the paster, means for pasting the running web to the fresh roll, means for severing the web from 15 the running roll, electrical circuits and a source of power for supplying power to effect operation of said means, a switching mechanism controlling all of said circuits, means for operating said switching mechanism by movement of said fresh roll to web renewing position, means for braking the running roll, controlled by said switching mechanism and means responsive to depletion of the running roll for initiating movement of the fresh roll.

25. 17. A control device for web renewing mechanism having a rotatable web roll support, comprising an electrical contact device non-rotatably mounted on the support, electrical circuits connected to a source of power and to said non-rotatable device and to the web renewing mechanism for controlling web renewing operations, and a circuit closing device mounted to rotate with said roll support and cooperating with said contact device to close said circuits, said device closing said circuits in a predetermined order to effect the complete web renewing operations.

18. A web renewing mechanism for a printing press having a rotatable reel supporting a running web roll in a running roll position and a fresh web 40 roll, electro-responsive means for rotating said reel to move the fresh roll toward the running web to make the paster and thereafter to running roll position, a source of power connected to said electro-responsive means, a circuit-controlling device 45 for controlling the power supplied to said means for rotating said reel upon depletion of the running roll, electrically controlled means for making the paster and switching mechanism for controlling the supply of power to said electrically 50 controlled means to energize said means in a predetermined order for renewing the web, said switching mechanism being operated by rotation of said reel, and means for slowing down the press to make the paster.

55. 19. In a machine for feeding a web to a printing machine and splicing it, the combination with a movable web roll support and means for operating it to move the web rolls, of electric means for controlling the motions of the support to bring 60 the running rolls successively and repeatedly from the running position into position to direct the web therefrom closely adjacent to a fresh roll preparatory to splicing the running web to the fresh roll, electric means for diverting the 65 running web against the pasted fresh roll for pasting, electric means for applying a brake to the exhausted stub, and electric means for severing the web laterally from the stub, the last three electric means being controlled by the first named 70 electric means.

20. In a machine for feeding a web to a printing machine and splicing it, the combination with a movable web roll support and means for operating it to move the web rolls, of electric means 75 for controlling the motions of the support to bring

the running rolls successively and repeatedly from the running position into position to direct the web therefrom closely adjacent to a fresh roll preparatory to splicing the running web to the fresh roll, electric means for diverting the running web against the pasted fresh roll for pasting, electric means for applying a brake to the exhausted stub, and electric means for severing the web laterally from the stub, the last three electric means being controlled by the first named 10 electric means.

21. In a web supply mechanism for a machine having a controller, a rotatable support for a plurality of web rolls, means for rotating the support to bring the rolls successively into running 15 position, a belt for accelerating the rotation of a web roll, pulleys arranged to support the belt, a magnetically operated driving connection for one of said pulleys, and control means for said driving connection operated by the rotation of the support.

22. In a web supply mechanism for a machine having a controller, a rotatable support for a plurality of web rolls, means for rotating the support to bring the rolls successively into running position, a belt for accelerating the rotation of a web roll, pulleys arranged to support the belt, a magnetically operated driving connection for one of said pulleys, and control means for said driving connection operated by the rotation of the support and by a switch electrically connected with the controller.

23. In a machine for feeding a web to a printing machine and splicing it, the combination with a movable web roll support and means for operating it to move the web rolls, of electric means for controlling the motions of the support to bring the running rolls successively and repeatedly from the running position into position to direct the web therefrom closely adjacent to a fresh roll preparatory to splicing the running web to the fresh roll, means for pressing the running web out of its normal path against the pasted fresh roll for splicing, electro-magnetic means for operating the last named means, and means controlled by the first named electric means for automatically starting the electro-magnetic means to actuate the web pressing means.

24. In a web supply mechanism, a rotatable web 50 roll support provided with rotating mechanism and adapted to rotatably carry a running roll and a replacement roll, control means for said rotating mechanism mounted on said support, a relay controlling said rotating mechanism and controlled by said control means, said control means and relay serving to initiate rotation of the support when the running roll is of a predetermined reduced diameter and continue said rotation until the replacement roll is in a desired position. 60

25. In a web supply mechanism, a rotatable web roll support provided with rotating mechanism and adapted to rotatably carry a running roll and a replacement roll, and control means for said rotating mechanism mounted on the support, a relay controlling said rotating mechanism and controlled by said control means, said control means and relay serving to initiate rotation of the support when the running roll is reduced to a predetermined diameter and continue said 65 rotation until the replacement roll is in running position.

26. In a web supply mechanism a web roll stand, a rotatable web roll support provided with rotating mechanism and adapted to rotatably 75

- support a running roll and a replacement roll, a motor for rotating the support, a member mounted on the support and adapted to move in contact with the running roll to supply power to the motor and to start the rotation of the support when the running roll has reached a predetermined diameter, a brush on the support connected with said member and a member mounted on said stand contacting with the brush, rotation of the support being stopped when the brush and second member separate.
27. In a web supply mechanism, a support for a running web roll and a replacement roll, control means operated automatically when the running roll is partially exhausted, a motor controlled thereby for rotating the roll support to move the replacement roll until the periphery of the replacement roll reaches a position near the web running from the running roll, and means controlled by the rotation of said support when the running roll approaches exhaustion for pressing the web therefrom against the replacement roll to make the join.
28. In a web supply mechanism a web roll stand, a rotatable support for a running web roll and a replacement web roll, a control switch, a commutator member electrically connected to the control switch, a brush holder member, one of said members being held against rotation, the other being rotatable with the support and one of the members being supported by the stand, and brushes carried by the brush holder movable axially of said support and engaging with the commutator.
29. In a web supply mechanism a web roll stand, a rotatable support for a running web roll

and a replacement web roll, a control switch, a commutator member and a brush holder member, one of which is secured to the stand and the other of which is mounted on the support to rotate therewith and brushes carried by the brush holder movable axially of said support and engaging with the commutator; the member that is secured to the stand being electrically connected to the control switch.

30. In a web supply mechanism a web roll stand, a rotatable web roll carrier adapted to rotatably support a running roll and a replacement roll, a motor for rotating said carrier, means engageable with the running roll for starting said motor when the running roll is reduced to a predetermined diameter, a brush on said support and means on the said stand contacting with said brush to interrupt the power supplied to the motor to stop rotation of the carrier when said means and brush lose contact.

31. In a web renewing mechanism, the combination of movable means for rotatably supporting an active web roll and a reserve web roll, brake means carried by the movable means for braking the web rolls, and means timed by movement of the support for applying the brake to one of the web rolls.

32. In a web renewing mechanism, the combination of rotatable means for rotatably supporting a plurality of web rolls, brake means carried by the rotatable means for braking the web rolls and means for energizing said brake means, said energizing means being controlled by the rotation of the supporting means.

WILLIAM A. ZALESAK.
